WESTON M. FULTON, OF KNOXVILLE, TENNESSEE, ASSIGNEE TO THE FULTON COMPANY, OF KNOXVILLE, TENNESSEE, A CORPORATION OF MAINE.

RADIATOR-CASING.

1,192,411.

Specification of Letters Patent. Patented July 25, 1916.

Application filed August 28, 1914. Serial No. 859,080.

To all whom it may concern:

Be it known that I, WESTON M. FULTON, a citizen of the United States of America, and a resident of Knoxville, Tennessee, have invented a new and useful Improvement in 5 Radiator-Casings, which invention is fully set forth in the following specification.

This invention relates to radiator jackets, and more particularly to jackets of this class 10 in which a thermostatic device, subject to room-temperature, is used for automatically operating dampers for controlling the flow of heated air through the jacket.

The invention has for its object to provide 15 a radiator casing of the above type in which the thermostatic element shall be free from sudden changes of temperature such as may arise from accidental cold drafts from open windows; and be protected from the direct 20 heat of the radiator as well as from stray heated convection currents therefrom, while at the same time it shall be subjected to air from the room at or near the average room-temperature.

25 My invention enables the above objects to be secured in an effective manner and, broadly stated, consists in providing in a damper-controlled radiator casing a chamber or extension of the casing partitioned 30 from the main part of the casing and into which air at average temperature of the room is drawn by convection currents set up in another part of the chamber, and locating in the chamber a thermostat for operating 35 the dampers where it may be subjected to the incoming cool air and insulating the same from the heating effects of the main chamber.

By way of illustrating one constructional 40 form of my invention, I provide a radiator casing, preferably one having a hood, with an extension or chamber closed at the bottom by an insulating door which extends beyond the pipe connections to the radiator, and 45 having an air inlet in the end wall near its top. The space in this extension is preferably partitioned from the main space in the casing by means of a specially formed end section of the radiator consisting of a hollow 50 wall which performs the double function of a heating section and a partition. This section is preferably located at the inlet end of the radiator. In this chamber is located a vertical insulating partition opposite the end 55 section of the radiator and extending to near

the floor of the chamber. This partition divides the chamber into two vertical compartments communicating at their bottoms. The outside compartment near its top is open to the room, and the inner compartment is 60 open to the hood space but is cut off from the main radiator space by the end wall of the radiator. The two compartments constitute a U-shaped conduit, one branch of which is in heat interchanging relation with 65 the radiator end section and opens into the hood of the casing; the other branch is open to the room. To secure the maximum difference of temperature between these two branches, whereby vigorous circulation of air 70 through the chambers may be secured, the partition separating the chambers is made of non-heat conducting material, such as cork. This also has the effect of shielding the thermostatic device from the heat of the 75 radiator and enables the device to respond more nearly to the temperature of the air entering the conduit from the room. To avoid transfer of heat by conduction through the connections between the thermostatic device and the dampers in the casing, the connections which pass through the wall separating the two spaces are preferably made of heat insulating material, or, if of metal, means are provided for circulating cool air 80 about the same. To avoid hot air escaping around the connection, I preferably provide a packing joint through which the connection may work. The thermostatic device is further protected from heated air in the 85 hood by making the top wall closing the compartment containing this device of heat-insulating material. As a result of this construction, the thermostatic device is enabled 90 to control the dampers of the casing practically uninfluenced by all forms of heat emanating from the radiator and is affected only by air from the room which represents very nearly the average room-temperature. 95

In order that the invention may be more 100 readily understood, reference is had to the accompanying drawings which illustrate one mechanical embodiment of the inventive idea. The drawings are merely intended to assist the description and not to define the 105 limits of the invention.

Figure 1 is a longitudinal vertical sectional view of a portion of a radiator casing constructed in accordance with my improvement and showing heating sections in eleva- 110

tion; Fig. 2 is a transverse vertical sectional view taken on line 2—2 of Fig. 1, showing the face of the end section of the radiator and the bottom pipe connections; 5 Fig. 3 is a perspective view with parts of the casing broken away to show the interior arrangement; and Fig. 4 is a top plan view with the hood removed, showing the arrangement of dampers and other parts.

10 In the drawings, Fig. 1 exhibits three radiator sections 1, 2 of the inclined ribbed type, and an end section 3 in the form of a hollow plate or wall, the bottom of which is connected with a pipe 4 of the heating system and preferably the inlet pipe. 5 is an end extension of the radiator casing adapted to fit snugly around the heating section 3 which separates the extension from the main radiator space of the casing and is 15 surrounded by an extension of the hood 6 of the casing. The bottom of this extension is closed by a floor 7 consisting of a plate of sheet metal lined with insulating material, such as cork or the like, and projects above 20 and beyond the inlet pipe connection 4. The space within the extension is divided into compartments 8 and 9 by means of a depending partition 10 which terminates just above the floor 7, thereby permitting communication at this point between the compartments. The compartment 8 is covered 25 by a wall 11 of insulating material like that mentioned, and has an opening 12 for admission of air at average room-temperature 30 provided near the top and in the end wall of the extension. Compartment 9 which is heated by the radiator opens into the hood space above it. 13 is a thermosensitive device adapted to be supported in compartment 8 near the entrance 12 and is provided with a connection 14 preferably of heat-insulating material, such as wood or other non-heat conducting material, which passes through the partition wall 10 and is 35 pivotally connected to a damper-operating lever 15 having operating connections with dampers 16 which control openings between the space heated by the radiator sections and the hood. To prevent heated air from 40 passing back from compartment 9 into compartment 8 and affecting the thermostatic device, the wall 10 is preferably provided with a packing box through which the rod 14 may tightly work. To facilitate the heating of air in compartment 9 and hasten air circulation past the thermostatic device, ribs 45 18 are provided on the end section 3 of the radiator.

The vertical walls of the casing extension 50 may, and preferably are, of sheet metal of single thickness, but their edges where they join the main casing should be heat insulated therefrom by means of asbestos strips 18', or similar material, for the purpose of 55 reducing as much as possible conduction of

heat from the casing walls to the walls of the extension.

The operation of my improvement will be readily understood from the above description and, briefly stated, is as follows:— 70 Steam or hot water having been admitted through inlet pipe 4 to the radiator, the end wall 3 imparts its heat to the air in compartment 9, thereby reducing its density and causing it to ascend into the hood space where it mingles with the hot air discharged through the openings in the hood. Cooler air taken from a level which approximates the average temperature of the room is drawn in through opening 12 and passes 75 around the thermostatic device. Circulation of a body of air is thus established independently of the circulation past the radiator sections. The thermostatic device responds to any variation of temperature of the incoming air from the room, and operates the dampers through its connections. The partition 10 effectively insulates the device from the heating effects of the radiator and heated air in compartment 9. The 80 floor 7 prevents convection currents set up around the heated connection 4 from finding their way to opening 12 and thence to the thermostatic device. The top wall of compartment 8 shields the device from the 85 heated air in the hood and heat conduction through connection 14 is avoided by making this connection of insulating material, while the side walls of the extension are insulated from the body of the casing by insulating strips 18. 90

What is claimed is:—

1. A radiator casing comprising a radiator-receiving portion provided with dampers and a second portion adapted to be separated therefrom by an end section of the radiator, said second portion having a floor of insulating material and a top wall, a vertical partition of insulating material dividing the space therein into a down-passage and an up-passage open to each other through said partition near said floor, one of said passages being in heat-interchanging relation with the end of the radiator and opening through said top wall, and the other passage being insulated from the radiator and opening through the end wall of the casing below said top wall to receive air from the room, and a thermostat located near the opening of the down-passage and operatively connected with said casing dampers. 105

2. A radiator casing comprising a radiator-receiving portion provided with dampers and a portion adapted to be separated therefrom by an end section of the radiator, means preventing conduction of heat from the walls of one casing portion to the other, said second portion having a floor of insulating material and a top wall, a vertical partition of in- 110

- sulating material dividing the space therein into a down-passage and an up-passage open to each other through said partition near said floor, one of said passages being in heat-
 5 interchanging relation with the end of the radiator and opening through said top wall, and the other passage being insulated from the radiator and opening through the end wall of the casing below said top wall to
 10 receive air from the room, and a thermostat located near the opening of the down-passage and operatively connected with said casing dampers.
3. A radiator casing comprising a radia-
 15 tor-receiving portion provided with dampers and a second portion adapted to be separated therefrom by the end section of the radiator, a hood surmounting both portions, heat insulating means preventing conduction of heat from the walls of one casing portion to the other, said second portion having a floor and a top wall both of insulating material, a vertical partition of insulating material dividing the space therein
 20 into a down-passage and an up-passage open to each other through said partition near the said floor, the up-passage being in heat-interchanging relation with said end section of the radiator and open to the hood through
 25 said top wall, and the down-passage being insulated from said radiator section and open below said top wall to receive air from the room, and a thermostat located in said down-passage near said opening and having
 30 connections with the casing dampers.
4. A radiator casing provided with dampers, a radiator therein having an end wall adapted to divide the casing into a radiator-receiving section and an extension thereof
 35 and provided with an inlet connection un-
- derneath the radiator, heat insulating means preventing conduction of heat from the walls of one casing section to the other, said extension section having a heat insulating floor located above and beyond said connection and a top wall, a vertical partition of heat insulating material dividing the extension space into a down-passage and an up-passage open to each other through said partition near the said floor, one of said passages opening through said top wall and in heat-interchanging relation with said radiator wall and the other insulated from the latter and open below said top wall to receive air from the room, and a thermostat located in said down-passage near said opening and having connections with the casing dampers.
5. A radiator casing provided with a hood and divided into a radiator-receiving chamber having openings into the hood, dampers controlling said openings, and an air circulating conduit open to said hood and having one portion in heat interchanging relation with the first-named chamber and another portion out of heat-interchanging relation with said first-named chamber for receiving air from the room, and a thermostatic device in the inlet end of the last-named portion of said conduit for controlling said dampers by variation of temperature of air entering from the room.

In testimony whereof I have signed this specification in the presence of two subscribing witnesses.
